UNITED STATES PATENT OFFICE.

ELECTUS D. LITCHFIELD, OF NEW CANAAN, CONNECTICUT.

TOY BLOCK.

1,124,631.

Specification of Letters Patent.

Patented Jan. 12, 1915.

Application filed March 31, 1914. Serial No. 828,434.

To all whom it may concern:

Be it known that I, ELECTUS D. LITCHFIELD, a citizen of the United States, and a resident of New Canaan, Fairfield county, Connecticut, have invented certain Improvements in Toy Blocks, of which the following is a specification, reference being had to the accompanying drawings, in which—

Figure 1 is a perspective showing three faces of a block made in accordance with my invention; Fig. 2 is another perspective of the block shown in Fig. 1; Fig. 3 is a perspective of another block made in accordance with my invention; Fig. 4 is another perspective of the block shown in Fig. 3, and Fig. 5 is a perspective view of a building constructed with the blocks shown in Figs. 1, 2, 3 and 4.

By my invention I produce toy blocks of uniform size and shape, from which buildings of various designs may be constructed. I have found these blocks to be useful in solving certain architectural problems, and also that said blocks make an exceedingly attractive toy for children.

The letters A and B represent cubical blocks which may be made of wood or pasteboard, having the faces A¹, A², A³, A⁴ and A⁵, and B¹, B², B³, B⁴ and B⁵. On these faces are printed or stamped the representations of various elements which go to make up the exterior of modern office buildings.

In the embodiment of my invention which is shown the block A may be used to show cornice sections of a building, and also to show ordinary window sections. On the faces A¹ and A² are the small windows 1, the large windows 2 and the cornices 3 and 4. The face A³ may be painted any solid color, to designate a roof structure. On the faces A⁴ and A⁵ are the small windows 1.

The block B may be used to show ground floor sections of a building, and also to show ordinary window sections of a similar structure. On the faces B¹ and B² of block B are the small windows 1, the round top win-

dows 5, the long round top windows 6 and the cornice 7. The face B³ of block B may be finished in like manner to the face A³ of block A, to represent a roof structure. On faces B⁴ and B⁵ of block B are small windows 1, similar to the small windows 1 shown on faces A⁴ and A⁵ of the block A.

In constructing a building with my blocks, the blocks B are used to represent the ground sections of the building, and when so used the faces B⁴ and B⁵ are turned inwardly so that they will not show. The central sections of the building may be constructed with either blocks A or blocks B. If blocks A are used the faces A¹ and A² are turned inwardly so that they will not show, and if the blocks B are used the faces B¹ and B² are turned inwardly so that they will not show. The cornice sections are constructed with blocks A, and when blocks A are used for this purpose faces A⁴ and A⁵ are turned inwardly so that they will not show.

It is evident that many variations may be made in the design of these blocks without departing from the spirit of my invention, since

What I claim is:

1. A cubical block having similar elements of architectural design on two adjacent faces and other elements of architectural design on other faces of the said block.

2. A block having similar elements of architectural design on two adjacent faces, and a second element of architectural design on two other adjacent faces.

3. A series of building blocks of uniform size and shape having a common element of architectural design on two adjacent faces of each of the said blocks, and other elements of architectural design on other faces of the said blocks.

ELECTUS D. LITCHFIELD.
